UNITED STATES PATENT OFFICE.

ERNST V. HILL, OF WORCESTER, MASSACHUSETTS, ASSIGNOR TO NATIONAL SALES MACHINE COMPANY, OF BOSTON, MASSACHUSETTS, A CORPORATION OF MASSACHUSETTS.

COIN-SELECTOR.

1,354,647.

Specification of Letters Patent.

Patented Oct. 5, 1920.

Application filed December 28, 1918. Serial No. 268,714.

To all whom it may concern:

Be it known that I, ERNST V. HILL, a subject of the King Sweden, residing at Worcester, in the county of Worcester and Commonwealth of Massachusetts, have invented a new and useful Improvement in Coin-Selectors, of which the following, together with the accompanying drawings, is a specification.

10 The present invention relates to devices for separating standard coins of a predetermined denomination from counterfeits, slugs, washers, and other spurious disk-like bodies of generally similar dimensions. The 15 present improvements are applicable to the type of coin selector fully illustrated and described in the United States Letters Patent to Reith, No. 1,236,870, dated August 14, 1917, and also in my copending application Serial No. 261,797, filed November 9, 1918.

The present invention embodies, in addition to the fundamental principles of the selector set forth in my aforesaid copending 25 application, certain novel principles relating to the accurate measurement and caliperizing of coins that are especially useful in connection with pieces of twenty-five cent denomination, both of the old and the new 30 United States coinage. In common with the machines of the Reith patent and my aforesaid copending application, the machine of the present invention is constructed on the duplex principle, *i. e.*, being so designed as 35 to accept standard coins of the same denomination, but of two different sets of dimensions. The machine of the present invention differs from the machine of my aforesaid copending application only as regards 40 the construction, arrangement, and principle of operation of the several coin measuring and caliperizing instrumentalities, and consequently, the description and drawings of the present application will be confined, as far as possible, to the instrumentalities 45 wherein such differences exist.

Figure 1 is an enlarged vertical section illustrating the coin measuring and caliperizing instrumentalities that constitute the essence 50 of the present invention.

Fig. 2 is a section on line 2—2, of Fig. 1.

Like reference characters refer to like parts in the different figures.

The detector mechanism in the present

machine is carried in the usual elongated 55 casing 1, which contains, as in the machines of the Reith patent and my aforesaid copending application, a stationary cylindrical barrel 2 and a movable cylindrical barrel 3. These barrels provide the similar co-operating sets of coin measuring instrumentalities that constitute the subject matter of the present invention; the varying amounts by which said instrumentalities are moved are availed of to control the position of opposite pairs of pendulums 4, 5, and 6, 7, of 60 the same character as the pendulums provided in the machines of the Reith patent and my aforesaid copending application. The ends of said pendulums are adapted to 70 co-operate with suitable sets of wards and recesses carried by a pair of valve controlling levers 8, 8, one adapted for movement in the case of a standard coin of one set of dimensions, and the other adapted for movement 75 in the case of a standard coin of the same denomination, but of a different set of dimensions, as in the machines of the Reith patent and my aforesaid copending application. 80

Said levers 8, 8, are operated upon by a spring 9 and at their ends are normally in engagement with a cam 10 on shaft 11, the rotation of which is communicated to the movable barrel 3 by means of a connecting 85 link 12, sleeve 13, spring 14, and plate 15, in precisely the same manner as described in the Reith patent and in my aforesaid copending application. The position assumed by the pendulums 4, 5, and 6, 7, and also the 90 positions assumed by a pair of thickness pendulums, not shown, that are controlled by the co-operating annular knife edges 16 of said barrels 2 and 3, are the determining factors in the movement of one or the other of the levers 8 against the low portions of cam 10. If the coin undergoing measurement is correct, one or the other of levers 8 will be allowed to move upwardly by said pendulums, and this movement is transmitted to a pivoted coin directing valve 17, 95 that operates, as in the machines of the Reith patent, and my aforesaid copending application. On the other hand, if the coin is spurious or does not correspond to either of the two sets of dimensions contemplated by the machine, neither of the levers 8, 8, is allowed to move, and the valve 17 is held in 100 105

such a position as to reject said coin. The instrumentalities which constitute the subject matter of the present invention and to which the movements of the several pendulums are delicately responsive, will now be described in detail.

Each barrel 2, 3, contains a plunger 18, which is of two diameters, slidably mounted in the barrel, and urged yieldingly outward by means of spring 19 bearing against shoulders 20 of said barrels. These plungers 18 contain the sets of measuring instrumentalities that make contact with the two faces of the coin when the latter is received between them, said coin being centered with respect to said plungers by means of a sliding block 21, carried by barrel 3, and said coin being gripped in said centered position by the knife edges 16, 16, precisely the same as in the machines of the Reith patent and my aforesaid copending application.

Each plunger 18 contains an inner slideable plunger mechanism which is constituted by a plurality of annularly arranged plunger sections or segments 22, the latter presenting an annular series of knife edges 23. Each plunger segment 22 has a flange portion 24 that bears against a shoulder 25 of plunger 18, being yieldingly held against said shoulder by means of a series of springs 26, operating on studs 27 that project outwardly from said flanges 24. The springs 26 are confined at their outer ends in recesses provided in plates 28 that close the end of each barrel 2, 3.

Inwardly of the segmental plungers 22 is disposed an annular plunger or sleeve 29, the periphery of which is provided with a plurality of longitudinal slots adapted to receive an annular series of pins 30. Threaded or otherwise secured to said sleeve 29, so as to cover and inclose said slots is a sleeve 31, which has a flange 32 adjacent and on the outer side of flange 24. Said flange 32 is apertured for the passage of the studs 27. Each pin 30 is provided with a head 33, normally held in contact with the end of sleeve 29 by means of an inwardly pressed pin 34 that carries a spring 35 operating between a shoulder 36 thereon and the plate 28. Said pins 34 take bearing in a flange 37 of another sleeve 38 that is disposed within the sleeve 29. Each flange 32 carries a stud 39 which passes freely through the adjacent flange 37 and makes contact with an adjustable screw 40 carried by a lever 41 that is pivoted at 42 in plunger 18. As in the machines of the aforesaid Reith patent and my aforesaid copending application, said levers 41, 41, are utilized to control the positions of one set of pendulums 6, 7, the longer arms of said levers projecting through slots in the barrels 2, 3, and being operated upon by springs 43.

65 The sleeve 38 projects rearwardly from a

centrally disposed plate 44, to which said sleeve is threaded or otherwise secured. Each plate 44 has an annular measuring edge 45, and is centrally apertured for the passages of a center pin 46. The flange 37 of sleeve 38 is adapted normally to engage a shoulder 47 of plunger 18, owing to the contact with said flange of a flange 48 that is carried by a member 49 in which the center pin 46 is secured. Said member 49 is pressed inwardly by means of a spring 50 operating against plate 28.

The flange 37 of sleeve 38 carries a member 51 that serves as a bearing for a lever 52, the latter being pivoted at 53 in said member 51 and carrying an adjustable screw 54 that makes contact with the flange 48. The two levers 52 whose longer arms project through suitable openings in the barrels 2, 3, and are operated upon by springs 55, serve 85 to control the positions of the pendulums 4, 5, in a manner similar to that set forth and described in the Reith patent, and in my aforesaid copending application.

The flange 48 carries an adjustable screw 90 56 that normally makes contact with the flange 32 of sleeve 31.

In addition to the mechanism above set forth each plunger 18 has slidably mounted therein a plurality of studs 57, here shown 95 as four in number, to the ends of which is secured a concentric coin guide 58 in surrounding relation to the knife edges 23. Said coin guide 58 is normally maintained at the limit of its inward movement by 100 springs 59, the other ends of which bear against flange 32 of sleeve 31. The limit of inward movement of the coin guide 58 is determined by heads 60 on the studs 57, which heads engage the shoulders of counterbored 105 holes in the plunger 18. The springs 59 pass through suitable clearance holes in the flanges 24 of sectional plungers 22. The object of providing these inwardly pressed guiding members 58 is to prevent the coin, 110 as it is dropped into the selector, from impinging against the various measuring edges and points that have been specified above.

When a coin is dropped into slot 61, its downward movement is arrested by suitable 115 devices, not herein shown, but fully described in the Reith patent and in my aforesaid copending application, so that it comes to rest in a central position with respect to the measuring points and edges above described. Under these conditions the coin directing valve 17 is in its normal position, namely, in the position adapted to direct the coin into the compartment reserved for spurious or counterfeit pieces. The levers 8, 8, 120 are prevented from moving under the action of spring 9, either because they are in engagement with the concentric part of cam 10, or because the ends of one or more of the pendulums 4, 5, 6, 7, and the thickness pen- 130

dulums, not shown, are opposite and in contact with the wards or projections carried by said levers.

Upon rotation of shaft 11 through slightly 5 more than a quarter of a revolution, the barrel 3 begins to move toward the barrel 2, it being noted that the movement of said shaft is transmitted through link 12 to the sleeve 13, spring 14, and plate 15, which later 10 first acts through spring 62 to move the block 21 toward the barrel 2, and thereafter acts to bodily move the barrel 3 in the same direction. This primary movement of the block 21 causes it to receive within its central cavity the coin which has been arrested in its passage through slot 61 by the arresting mechanism, not shown. The subsequent movement of the barrel 3 with its knife edges, pins and other measuring instrumentalities into engagement with the coin occurs 15 while the shaft 11 is so moving that the link 12 is approaching a horizontal position, or during the first half of the forward movement of crank 63 on said shaft. As said movement is continued through its last half, the link 12 operates to retract the barrel 3, and the arresting mechanism, not shown, is thereupon retracted from the slot 61 so as to permit the gravity descent of the coin into 20 the valve 17. As the barrel 3 begins its movement toward the barrel 2, by force applied through plate 15, the knife edges 16 are brought into engagement with the outer part of the coin just inside of its rim or 25 flange, thus firmly gripping and holding the coin within the cylindrical cavity of block 21. The engagement of these knife edges with the coin determines the amount of inward movement of barrel 3, and as described 30 in the Reith patent and in my aforesaid pending application, a pair of thickness pendulums, not herein shown, since they form no part of the present invention, are made responsive to this movement in such a manner 35 as to permit the lifting of either one of the levers 8 if the thickness thus measured corresponds to the predetermined standard,—provided of course the other pendulums 4, 5, and 6, 7, will permit of this movement. These other pendulums are controlled 40 as above stated by the novel coin measuring instrumentalities above described of the barrels 2 and 3, the action of which will now be set forth in detail.

The segmental knife edges 23 of plunger sections 22 are pressed inwardly against the opposite faces of the coin for variable distances, depending upon the relief of the coin at the different parts of the circle engaged by said knife edges. In other words, the various plunger sections 22 will occupy different relative longitudinal positions when their respective knife edges are in contact with the face of the coin; one of these plunger sections 45 will obviously take up a position determined by the minimum relief of the coin on the circle engaged, and another will take up a position determined by the maximum relief of the coin on the circle engaged. The plunger portion 22 which is farthest held outwardly by the maximum relief of the coin acts through its flange 24, bearing against flange 32, to force the stud 39 outwardly. The movement of stud 39 is transmitted to the adjustable screw 40 to rock the lever 41 about its pivot, this applying obviously to both levers 41, and thereby controlling either the pendulum 6 or the pendulum 7, as the case may be.

Also, this plunger portion 22 which is farthest moved outwardly acts through its flange 24, bearing against flange 32, to move the stud 56 outwardly. The flange 48 to which said stud is secured, responds to this movement and thereby through adjustable screw 54 rocks the lever 52 about its pivot, this applying obviously to both levers 52, and thus affects a control of either the pendulum 4 or the pendulum 5, as the case may be. It will thus be seen that the maximum relief of the coin on the circle engaged by the sectional knife edges 23 results in a control of both sets of pendulums 4, 5, and 6, 7.

On the other hand, that plunger portion 22 which is least moved outwardly, as determined by the minimum relief of the coin on the circle engaged by sectional knife edges 23 assumes a position which permits a limited movement of plunger 18, under the action of springs 19, which tend to keep the shoulder 25 in contact with flange 24. This outward movement of plunger 18 changes the position of the pivot points 42. Obviously such a change in the positions of the pivot points of the levers 41 results in a variation of the movement of the long arms of said levers that would not otherwise occur, and consequently the control of the pendulums 6, 7, is affected accordingly. From the above, it will be seen that the minimum relief of the coin on the circle engaged by the knife edges 23 results in a control of either the pendulum 6 or the pendulum 7, as the case may be. There is thus produced, in connection with the sectional knife edges 23 a control of pendulums 4, 5, arising out of the maximum relief of the coin on the circle engaged by said knife edges, and also a dual control of pendulums 6, 7, arising out of both the maximum and the minimum relief of the coin on the circle engaged by said knife edges.

The next smallest measuring circle is that engaged by the ends of the pins 30, which are moved outwardly by the coin relief against the pressure of springs 35. That pin 30 which moves the least, as determined by the minimum relief of the coin on the circle engaged by said pins, will limit the movement of flange 32 under the action of springs 130

59, due to the contact of head 33 with said flange. This limited movement of flange 32 is transmitted through stud 39, contacting with adjustable screw 40, to rock the lever 41 about its pivot, this applying obviously to both levers 41 and thereby effecting a control of either the pendulum 6 or the pendulum 7, as the case may be. Also, this movement of flange 32 is transmitted to the stud 10 56 to move the flange 48, against which bears the adjustable screw 54 of lever 52. In this way a simultaneous control of either pendulum 4 or the pendulum 5 is obtained. It will thus be seen that the minimum relief of 15 the coin on the circle engaged by the pins 30 is availed of to control the movements of both pairs of pendulums 4, 5, and 6, 7.

On the next smallest measuring circle the annular measuring edge 45 of plate 44 makes 20 contact with a coin, and the degree to which said plate is thus held outwardly, as determined by the maximum relief of the coin on the circle engaged, is available for the control of pendulums 4 or 5, as the case may 25 be. The movement of plate 44 is transmitted through sleeve 38 to flange 37. The flange 37 carries the member 51, on which the lever 52 is pivoted. Consequently there is a shifting of the pivots of the two levers 30 51, with a resultant control of the pendulums 4, 5. Also, this movement of flange 37 is transmitted to the flange 48, against which bears the adjustable screw 54 of lever 52. Therefore simultaneously with the 35 shifting of the pivots of levers 52, there is a rocking of said levers about their pivots, with a consequent control of pendulums 4, 5. It will thus be seen that the maximum relief of the coin on the measuring circle 40 engaged by the edge 45 is responsible for a dual control over the pendulums 4, 5.

At the innermost point of contact with the coin, namely, that engaged by the center pin 46, the member 49 is pressed outwardly, 45 such motion being transmitted through flange 48, contacting with adjustable screw 54 to rock the levers 52 about their pivots. This imposes an additional control on the movements of pendulums 4 and 5. Therefore 50 there is, in connection with the pendulums 4, 5, a control exercised by the plunger portions 22, the pins 30, the plate 44, and the center pin 46, the control due to the plate 44 being a dual control, as described above. 55 Also, in connection with the pendulums 6, 7, there is exercised a control by the plunger portions 22 and by the pins 30, that by the plunger portions 22 being a dual control which is responsive both to the maximum 60 and to the minimum relief of the coin on the circle engaged by the sectional knife edges 23.

In the present embodiment of the invention, applied to a machine of the duplex type, as illustrated in the Reith patent and 65

in my aforesaid copending application, it is obvious that it is immaterial in what manner the coin is presented to the slot 61, whether with its head side or its tail side facing the front of the machine. It is also obvious that for a given coin, such as a twenty-five cent piece of the old United States coinage, one of the levers 8 will be allowed to rise, while for another coin of the same denomination, but different measurements, such as a twenty-five cent piece of the new coinage, the other lever 8 will be allowed to rise. In this respect the machine of the present invention partakes of the same duplex principle as the machines of the Reith patent and my aforesaid copending application. Since said principle constitutes no part of the present invention, a detailed elaboration thereof is deemed unnecessary.

I claim,—

1. In a coin selector, the combination with two sets of mechanism operative to control the acceptance or rejection of a coin, of means for determining the action of one of said sets in accordance with the minimum relief of a group of points on said coin, and means for determining the action of both of said sets in accordance with the maximum relief of the same group of points.

2. In a coin selector, the combination with two sets of mechanism operative to control the acceptance or rejection of a coin, of means for determining the action of one of said sets in accordance with the minimum relief of the coin on a circle of predetermined radius, and means for determining the action of both of said sets in accordance with the maximum relief of the coin on the same circle.

3. In a coin selector, the combination with two sets of mechanism operative to control the acceptance or rejection of a coin, of means for determining the action of one of said sets in accordance with the minimum relief of a group of points on said coin, and means for determining the action of both of said sets in accordance with the minimum relief of a different group of points on said coin.

4. In a coin selector, the combination with two sets of mechanism operative to control the acceptance or rejection of a coin, of means for determining the action of one of said sets in accordance with the minimum relief of the coin on a circle of predetermined radius, and means for determining the action of both of said sets in accordance with the minimum relief of the coin on a circle of different radius.

5. In a coin selector, the combination with two sets of mechanism operative to control the acceptance or rejection of a coin, of means for determining the action of one of said sets in accordance with the maximum relief of a group of points on said

coin, and means for determining the action of both of said sets in accordance with the maximum relief of a different group of points on said coin.

maximum relief of a group of points on said coin, and means for determining the action of both of said sets in accordance with the minimum relief of a different group 55 of points on said coin.

11. In a coin selector, the combination with two sets of mechanism operative to control the acceptance or rejection of a coin, of means for determining the action 60 of one of said sets in accordance with the maximum relief of a group of points on said coin, means for determining the action of both of said sets in accordance with the maximum relief of another group of 65 points on said coin, and means for determining the action of both of said sets in accordance with the minimum relief of a third group of points on said coin. 10

12. In a coin selector, the combination 70
with two sets of mechanism operative to
control the acceptance or rejection of a coin,
of means for determining the action of one
of said sets in accordance with the minimum
relief of a group of points on said coin, 75
means for determining the action of the
other of said sets in accordance with the
maximum relief of a different group of
points on said coin, and means for deter-
mining the action of both of said sets in 80
accordance with the maximum relief of said
first mentioned group of points.

13. In a coin selector, the combination with two sets of mechanism operative to control the acceptance or rejection of a coin, of means for determining the action of one of said sets in accordance with the minimum relief of a group of points on said coin, means for determining the action of the other of said sets in accordance with the maximum relief of a different group of points on said coin, and means for determining the action of both of said sets in accordance with the minimum relief of a third group of points on said coin. 95
